2 Sheets-Sheet 2

UNITED STATES PATENT OFFICE

CHARLES A. BONDZIULIS, OF WATERBURY, CONNECTICUT

AUTOMATIC STOP FOR DOUBLE-PILE-FABRIC LOOMS

Application filed September 30, 1929. Serial No. 396,089.

This invention relates to improved automatic stops for double-pile-fabric looms which are characterized by having a pile-cutting knife for cutting the double-pile fabric into two single-pile fabrics, and constitutes an improvement upon the device shown and described in United States Patent No. 1,635,396, granted to me July 12, 1927.

The object of this invention is to provide a simple and reliable stop-mechanism for double-pile-fabric looms which will function to automatically stop the loom and thus prevent damage to the fabric being woven, should the propelling cord of the pile-cutting knife be broken or displaced for any reason, and which will be characterized by low cost for manufacture, ease and simplicity of installation, and sureness of operation.

With this object in view, my invention consists in an automatic stop for double-pile-fabric looms having certain details of construction and combinations of parts as will be hereinafter described and particularly recited in the claims.

25 In the accompanying drawings:

Fig. 1 is a schematic view mainly in front elevation of my improved automatic stop shown as applied to a double-pile-fabric loom, the parts being shown in the positions due them under ordinary operating conditions;

Fig. 2 is an enlarged-scale broken sectional view taken on the line 2—2 of Fig. 1;

Fig. 3 is a similar view but showing the parts in the positions due them when the trip-arm has been interposed in the path of the reciprocating reed-beam by slackness in the knife-cord;

Fig. 4 is an enlarged-scale sectional view 40 taken on the line 4—4 of Fig. 1;

Fig. 5 is a broken plan view of the shelf or ledge with the control-lever in section;

Fig. 6 is a vertical sectional view taken on the line 6—6 of Fig. 1; and

Fig. 7 is a broken face view showing a construction in which the operating-cord is directly connected to the trip-arm.

In carrying out my invention as herein shown, a loom-control box 10 contains appropriate mechanism such as a clutch or elec-

tric switch for stopping and starting the loom. This mechanism, whatever its character, is operated by a control-lever 11 extending upward through a clearance-slot 12 in a shelf or ledge 13 forming a part of the loom-frame. The slot 12 is formed with a laterally-offsetting notch providing a shoulder 14 for holding the control-lever 11 in its "on" position against the tension of a spring 15 which tends to move it into its "off" position which is indicated by broken lines in Fig. 1.

Depending from the under-face of the shelf or ledge 13 is an L-shaped bracket 16 carrying at its lower end a guide-block 17 having a guide-passage 18 extending from front to rear therethrough and enlarged at its front and rear ends to form recesses 19 and 20 respectively.

Reciprocating in the guide-passage 18 is a trip-plunger 21 formed near its rear end with a flange 22 against the forward face of which a helical spring 23 bears. The spring 23 just referred to encircles the trip-plunger 21 and bears at its forward end against the bottom of the recess 20 in the block 17 and serves to normally hold the plunger 21 in its rearwardly-extended position, as shown in Fig. 2.

To limit the rearward movement of the plunger, I mount upon the forward end thereof by means of a pin 24, a collar 25 which is adapted to fit within the recess 19 and engage the bottom-wall thereof.

At the extreme rear end of the trip-plunger 21 which has capacity for both oscillating and reciprocating movement in the guide-block 17, is a rectangular trip-arm 26 secured thereto by a depending pin 27 and formed in its outer end with a latching-notch 28 adapted to receive the free outer end of a pivotal 85 latch-bar 29 mounted by means of a pin 30 for swinging movement in the horizontal plane upon a lateral arm 31 offsetting from the guide-block 17 aforesaid.

The arm 31 of the guide-block 17 is formed with a rearward extension 32 to which is secured one end of a helical spring 33, the opposite end of which is secured to the depending lower end of the pin 27 which serves to secure the trip-arm 26 to the trip-plunger 21.

The spring 33 exerts a constant effort to swing the trip-block from its horizontal position in which it is shown in Fig. 2 to its vertical position shown in Fig. 3, so as to interpose it in the path of the reciprocating reed-beam 34 forming a usual feature of looms. To check the upward swinging movement through the trip-arm 26, I provide a stop-arm 34^a which rearwardly offsets from the guide-block 17 (Fig. 4).

10 A pile-cutting knife 35 is reciprocated in the usual manner of double-pile-fabric looms as required to cut a double-pile fabric 36 into two separate single-pile fabrics 37 and 38, such as velvet, plush, or similar material (Figs. 2 and 3), by means of a cord or cable 39 passing over a floating idler-pulley 40 having capacity for vertical movement, as will be hereinafter described, and over idler-pulleys 41, 20 42, 43, 44, 45, and around an oscillating drum 46 by means of which the cord 39 and hence the knife 35 is moved first in one direction and then in the other to sever the double-pile fabric 36 as woven, into the two single-pile 25 fabrics 37 and 38.

The floating idler-pulley 40 is mounted for vertical sliding movement between the opposite side-bars 47 and 48 of a guide-frame 49 which is provided with an offsetting boss 50 30 provided with a vertical passage 51 for vertical sliding movement upon the depending arm of an L-shaped bracket 52 secured to the under-face of the shelf or ledge 13. A set-screw 53 passing through the forward end of the offsetting boss 50 serves to clamp the guide-frame 49 in any one of a variety of 35 positions of vertical adjustment.

The said floating idler-pulley 40 is also 40 mounted for rotation upon a short transverse shaft 54 flattened at its respective opposite ends for sliding movement in vertical slots 55 and 56 formed in the side-bars 47 and 48 respectively of the guide-frame 49.

Connected to the rear end of the shaft 54 45 is an operating-cord or cable 57 running over a small pulley 58 secured to the upper end of the side-bar 47. The opposite end of the operating-cord or cable 57 is secured to the free inner end of the pivotal latch-bar 29, 50 as clearly shown in Figs. 1 and 4 of the drawings.

Under ordinary operating conditions, the 55 cord 39, by passing underneath the floating idler-pulley 40, will maintain the same near the upper end of the guide-frame 49 and hence relieve the operating-cord 57 of tension so that the latch-bar 29 remains in place in the notch 28 of the trip-arm 26, whereby the 60 same is held in a horizontal position against the counter-urge of its spring 33 and hence below the path of the reciprocating reed-beam 34 which is provided with reeds 59 acting in the usual manner to "beat up" the filling threads of the fabric 36 as it is being woven.

65 In the event that the knife-cord 39 should

break or for any reason become dismounted from its pulleys in such manner as to cause slackness in its tension, it will permit the floating idler-pulley 40 to descend in the guide-frame 49 with the effect of drawing 70 upon the operating-cord 57 and hence swing the free end of the latch-bar 29 out of the notch 28 of the trip-arm 26 so as to permit the same to be swung by the spring 33 from the position shown in Figs. 1, 2 and 4 of the drawings into its vertical position, as shown in Fig. 3 of the drawings. In this latter position, the upper end of the trip-arm 26 lies in the path of the reciprocating reed-beam 34 and will be engaged thereby with the effect of sliding the trip-plunger 21 from rear to front to cause the same to move the control-lever 11 out of engagement with the shoulder 14 of the slot 12, thus releasing the 80 said control-lever to the action of its spring 15 by which it is swung into its "off" position, as shown by broken lines in Fig. 1. The loom is thus automatically brought to a stop before any appreciable damage to the fabric 85 being woven can occur.

Instead of latching the trip-arm 26 in its horizontal position and providing a spring for swinging it into its vertical position when unlatched, I may, if desired, omit the said latch and spring and connect the operating-cord or cable 57 directly to the lower end of the pin 27, as shown in Fig. 7 of the drawings, so that when the floating idler-pulley 40 is permitted to descend by gravity when the tension of the knife-cord 39 is slackened for any reason, the weight of the descending pulley 40 will act directly to swing the trip-arm 26 into its vertical position so as to interpose its upper end in the path of the reciprocating reed-beam 34.

105 By providing a plunger which is mounted for both oscillating and reciprocating movement and providing the same with an offsetting arm, I am enabled to dispense with the cumbersome and complicated mechanisms heretofore employed for the purpose of automatically stopping double-pile-fabric looms.

110 I claim:

1. In a double-pile-fabric loom, the combination with a power-control mechanism, pile-cutting knife-cord, and reed-beam thereof; of a stationary guide-member; a trip-plunger mounted for both oscillating and reciprocating movement in the said guide-member in position to co-act with a part of the said control-mechanism to cause the same to move into its "off" position; an arm secured to and laterally-offsetting from said plunger and normally lying out of the path of movement of the said reed-beam; and means brought into play by the slackness in the said knife-cord for turning the said plunger to swing its offsetting arm into the path of the said reed-beam for actuation thereby.

115 2. In a double-pile-fabric loom, the combi- 120

nation with a power-control mechanism, pile-cutting knife-cord, and reed-beam thereof; of a stationary guide-member; a trip-plunger mounted for both oscillating and reciprocating movement in the said guide-member in position to co-act with a part of the said control-mechanism to cause the same to move into its "off" position; an arm secured to and laterally-offsetting from said plunger and normally lying out of the path of movement of the said reed-beam; yielding means normally tending to turn the said plunger so as to swing its offsetting arm into the path of the said reed-beam; a latch for holding the said offsetting arm in its reed-beam-clearance position; and means brought into play by slackness in the said knife-cord for retracting the said latch to permit the said yielding means to turn the said plunger in a direction to swing its offsetting arm into the path of the said reed-beam.

In testimony whereof, I have signed this specification.

CHARLES A. BONDZIULIS.
